United States Patent Office.

HUGH B. WILLSON, OF NEW YORK, N. Y.

Letters Patent No. 72,142, dated December 10, 1867; antedated November 28, 1867.

IMPROVEMENT IN VENTILATING TUNNELS.

The Schedule referred to in these Letters Patent and making part of the same.

TO ALL WHOM IT MAY CONCERN:

Be it known that I, HUGH BOWLBY WILLSON, of the city and county of New York, in the State of New York, have invented a new and improved Method of Ventilating Railway-Tunnels constructed underneath the streets or other parts of cities and towns; and I do hereby declare that the following is a full and exact description thereof, reference being had to the accompanying drawings, making a part of the specification, in which—

A represents a cross-section of a street-railway tunnel.

B B the columns for receiving and discharging the air in the manner hereinafter specified, which columns it is intended shall be substituted for the lamp and awning-posts before in use, and which may be applied to any other use, or for ornament; and

C C are the pipes connecting alternately with the top and bottom; or other part of such tunnels, the former arrangement being preferred.

The nature of my invention consists in erecting over or near the outer walls of such railway-tunnels hollow columns or pillars, constructed of iron or other suitable material, and connecting the same on the opposite sides of the tunnel, alternately or otherwise, with the top and bottom, by means of pipes constructed of any suitable material, which columns and their connecting pipes may be placed as near to each other as may be deemed necessary to secure adequate ventilation.

When such railway-tunnels run underneath a street, the columns may be made highly ornamental, and being placed on the sidewalks, near the curb-stones, may be and are intended to be substituted for lamp-posts and awning or other posts.

The openings for the ingress of fresh air, and the escape of foul or vitiated air, may be made at the bases of the columns, as shown in the drawings, or, the columns being carried up of a sufficient size, and being hollow, the openings may be made at the capitals or tops, just below the lamps in the case of lamp-posts.

I do not confine or limit myself to any particular size, form, or height of column, or ventilating lamp, awning, or other post applicable to the purposes of ventilating railway-tunnels in manner specified, nor to any particular material for their construction, or of the connecting-tubes, nor do I claim as new the construction of hollow lamp, awning, or other posts, pillars, or structures; but

What I do claim as my invention and improvement, is—

1. The method of applying street-lamp posts, and awning and other useful or ornamental posts, pillars, or structures to the purposes of ventilating underground railway-tunnels, substantially as within described.
2. I claim the combination of street-lamp posts, and awning and other posts, pillars, or structures, whether for ornament or use, with the connecting-tubes of such railway-tunnels, substantially in manner set forth.

HUGH B. WILLSON.
